CLAIM

The ornamental design for a fastener for an orthopedic brace, as shown and described.

DESCRIPTION

FIG. 1 is a perspective view of a design for a fastener for an orthopedic brace.

FIG. 2 is a front elevational view thereof.

FIG. 3 is a rear elevational view thereof.

FIG. 4 is a left side elevational view thereof.

FIG. 5 is a right side elevational view thereof.

FIG. 6 is a top plan view thereof.

FIG. 7 is a bottom plan view thereof.

FIG. 8 is a perspective view thereof.

FIG. 9 is a perspective view thereof in a position of use; and, FIG. 10 is another perspective view thereof in an alternate position of use.

In the drawings, the broken lines showing an orthopedic brace in FIG. 9 and FIG. 10 are for the purpose of depicting environment and form no part of the claim.
